UNITED STATES PATENT OFFICE.

FRANK W. SHIREY AND JOHN W. DODD, OF TULSA, OKLAHOMA.

ROPE-SOCKET.

1,061,134.

Specification of Letters Patent.

Patented May 6, 1913.

Application filed June 21, 1912. Serial No. 705,086.

To all whom it may concern:

Be it known that we, FRANK W. SHIREY and JOHN W. DODD, citizens of the United States, residing at Tulsa, in the county of 5 Tulsa and State of Oklahoma, have invented new and useful Improvements in Rope-Sockets, of which the following is a specification.

Our invention relates to rope sockets, the 10 main object being to provide cushioning means within the body of the device adapted to relieve the strain on the rope at the instant upward movement is given to the same, or when the device becomes engaged 15 with an obstruction in its upward travel.

A further object is the provision of means 20 for preventing slackening in the rope upon sudden impact of the tool attached to the socket.

25 A still further object is the provision of the means for equalizing the air pressure within the body of the socket due to the reciprocation of the plunger mounted therein, said means further serving to ventilate the device and prevent undue heating of the same.

Another object of the invention is to provide a reciprocating plunger within the 30 socket body having an enlarged head thereon provided with a downwardly opening tapered socket communicating with a longitudinal bore in the plunger, a cone member attached to the lower end of the supporting cable which extends through the plunger 35 bore and the cone adapted to be received within the said socket, and means carried by the said cone and adapted for engagement within the slots provided in the body for preventing rotation of the said body with 40 respect to the cable.

Further objects of the invention will appear as the following description is read in connection with the accompanying drawings, in which:—

45 Figure 1 is a front elevation of the device. Fig. 2 is a longitudinal sectional view taken on the line 2—2 of Fig. 1. Fig. 3 is a transverse sectional view on the line 3—3 of Fig. 1.

50 In the drawing, 1 designates a rope socket, which consists in part of the cylindrical coupling member 2. The member 2 is provided with a central bore 3, the lower portion of which is enlarged as at 4. A tapered 55 socket 5 is formed in the lower end of the

member 2 in communication with the enlarged portion 4 of the bore thereof, and which is adapted to receive the threaded extremity of a drill tool or a reducing sub. The member 2 is also provided with diametrically opposite longitudinally extending rows of transverse openings 6 for a purpose hereinafter fully described.

A hollow plunger 7 comprising a cylindrical body 8 and an enlarged head 9 formed 60 on the lower end of the body, is adapted to be slidably mounted within the bore of the member 2. In this position the body 8 is received by the reduced portion 3 of the bore and the cylindrical head 9 is received 65 by the enlarged portion 4 thereof. A helical spring 10 surrounding the body 8 of the plunger is interposed between the shoulder 11 formed by the head and the shoulder 12 formed at the juncture of the enlarged portion 4 with the portion 3 of the said bore. This spring is adapted to normally maintain the head 9 of the plunger in its lowermost position midway of the enlarged bore 4. A tapered socket 13 is provided in the 70 head 9 of the plunger in alignment with the longitudinal opening or bore of the plunger body, and is intended for the reception of a cone 14 fixedly secured to the lower end 75 of the rope 15 which extends downwardly 80 through the bore of the plunger.

The cone 14 when in position within the plunger socket extends below the lower end thereof, this extension being provided with a transverse longitudinally extending slot 85 16 for the reception of a cross head 17 which is secured therein against the upper edge 18 of the slot by means of the bolt 19. When secured in this position, the upper edge of 90 the cross head is adapted to engage the lower end of the plunger to prevent a cone from becoming wedged too tightly therein, and its ends 20 are slidably movable within the diametrically opposite, longitudinally 95 extending guide grooves 21 provided in the body in communication with its central bore 100 and extending longitudinally with respect thereto. This cross head limits the body to vertical motion with respect to the cone and consequently the tool, it being secured against rotary motion with respect thereto.

The slots 21 extend downwardly into the tapered, threaded socket 5 so that, upon detachment of the socket body from the tool 105 with which it is used, the cone may be drawn 110

outwardly through the socket 5 and the cross head removed in case it becomes necessary to repair or replace the same.

We claim:—

- 5 1. A rope socket comprising a coupling member having a longitudinal bore, a plunger reciprocally mounted in said bore, said plunger having a longitudinal bore, a head formed on the lower end of said plunger 10 and provided with a downwardly diverging tapered socket, a cone reciprocally mounted in said socket, a rope extending downwardly through said plunger with its lower end attached to said cone, and cushioning means 15 normally maintaining said plunger in its lowermost position in the bore of the coupling member.
2. A rope socket comprising a one-piece coupling member having a longitudinal bore, the lower portion of said bore being 20 enlarged, a plunger including a body portion and an enlarged head on the lower end thereof, said plunger being reciprocally

mounted in the bore of said member, the head being received by the enlarged portion of the bore, said plunger adapted to be removed through the lower end of said bore, said plunger having a central bore terminating downwardly in a tapered socket, a cone reciprocally mounted in said socket, a rope 30 extending downwardly through the plunger with its extremity secured to the apex of said cone, and a helical spring within the enlarged bore of the coupling member 35 surrounding the plunger body and interposed between the head thereof and the shoulder formed at the juncture of the said enlarged portion of the bore with the reduced portion.

In testimony whereof we affix our signatures in presence of two witnesses.

FRANK W. SHIREY.
JOHN W. DODD.
